UNITED STATES PATENT OFFICE.

JAMES TIMMS, OF COLUMBUS, OHIO.

DESIGN FOR A DRAW BAR AND HEAD FOR CAR-COUPINGS.

SPECIFICATION forming part of Design No. 35,149, dated October 1, 1901.

Application filed June 27, 1901. Serial No. 66,289. Term of patent 14 years.

To all whom it may concern:

Be it known that I, JAMES TIMMS, of Columbus, in the county of Franklin and State of Ohio, have invented and produced a new and original Design for a Draw Bar and Head for Car-Couplings; and I do hereby declare the following to be a full, clear, and exact description of the invention, such as will enable others skilled in the art to which it appertains to make and use the same.

In the accompanying drawings, Figure 1 is a top plan view showing the design of a draw bar and head for car-couplings. Fig. 2 is a bottom plan view, and Fig. 3 is a sectional view on the line $x-x$ of Fig. 1.

The draw-bar 1 projects rearwardly from the draw-head 2 and consists of a hollow elongated body tapering somewhat toward its rear end and having flat faces disposed at right angles to each other. At the rear end

enlargements 3 3 protrude from the upper and lower faces of the draw-bar, and in each of these enlargements are circular depressions 4 4, each having its wall disposed at right angles to its base. At points intermediate of the ends of the draw-bar there are elongated slots 5 in the upper and lower faces.

Having described my design, what I claim as new, and desire to secure by Letters Patent, is—

The design for a draw bar and head for car-couplings herein shown and described.

In testimony whereof I have signed this specification in the presence of two subscribing witnesses.

JAMES TIMMS.
